LOCOMOTIVE COMBUSTION REGULATOR

Filed Dec. 1, 1921

FIG. 2.

FIG. 3.

Inventor
E. T. D. Myers, Jr.

By
Sturtevant & Mason Attorneys

UNITED STATES PATENT OFFICE.

EDMUND T. D. MYERS, JR., OF RICHMOND, VIRGINIA.

LOCOMOTIVE COMBUSTION REGULATOR.

Application filed December 1, 1921. Serial No. 519,117.

To all whom it may concern:

Be it known that I, EDMUND T. D. MYERS, Jr., a citizen of the United States, residing at Richmond, in the county of Henrico, State 5 of Virginia, have invented certain new and useful Improvements in Locomotive Combustion Regulators, of which the following is a description, reference being had to the accompanying drawing and to the figures of 10 reference marked thereon.

This invention relates to new and useful improvements in combustion regulators for use on steam locomotives so as to effect material economy in the use of fuel and water 15 and the reduction of waste of steam through the pop valve and its resulting noise; as well as the abatement of smoke and gas issuing from the stack in localities where, for the time being, extreme steam pressure is not 20 absolutely needed and an excess of smoke and gas from the stack is peculiarly objectionable—such as in tunnels, train sheds and towns.

Locomotives are equipped with a spacious 25 compartment forward of and secured to the boiler called the "smoke box", into which the flues from the firebox discharge the smoke and gas, and also through a centrally located part of which the exhaust steam 30 from the driving cylinders passes by means of passages converging to a single discharge opening called the exhaust nozzle. This exhaust nozzle is placed somewhat below the bottom of the stack and on the same vertical 35 axis with it. In addition to the natural draft passing in sequence through the grates, the fire, the firebox, the flues, the smoke box and finally the stack, a forced draft is obtained when the driving cylinders are using 40 steam, by the rapid discharge of the jet of the expanding exhaust steam vertically from this exhaust nozzle through a small portion of the smoke box and thence through the stack. This discharge causes a partial 45 vacuum in the smoke box which is filled with air rushing through the grates, the firebox and flues, thus promoting and intensifying the rate of combustion of the fuel. While a primary object in locomotive design is to 50 cause the combustion to be as rapid as possible when the driving cylinders are working at or near their maximum capacity, the draft is at times excessive and causes the rate of generation of steam in the boiler to exceed that of its consumption by the cylin-

ders, and the steam pressure in the boiler then reaches the limit of safety and the usual pop valve opens and wastes the excess steam to the atmosphere. It is the object of a careful fireman to keep the boiler pressure nearly up to the safety-valve limit and yet not high enough to cause wasteful discharge, and also in case of light train loads, descent of grades or standing still, to keep the pressure even lower, thus conserving 60 fuel. The firemen are strictly required to use every effort to prevent unnecessary waste at the pop-valve and it is well known that this is difficult of accomplishment.

In an application filed by me July 22, 70 1921, Serial Number 486,912, I have disclosed a combustion regulator for a modern type of steam locomotive comprising a small auxiliary pop-valve therefor, set to go off at a steam pressure slightly below the discharge pressure of the main pop-valve. This auxiliary pop-valve is connected by suitable piping to the smoke box, so that when the auxiliary pop-valve operates, the vacuum in the smoke box will be reduced 75 and the draft through the firebox correspondingly moderated. In addition, the pipe connection between the auxiliary pop-valve and the smoke box is provided with an ordinary globe valve for suitably and finally regulating by actual trial the amount of steam passing therethrough, said valve to be then permanently fixed by any convenient means so as to prevent the operatives changing its extent of opening. And there is further 80 provided a manually controlled by-pass from the source of boiler pressure to the pipe discharging into the smoke box so steam may be passed around the auxiliary pop-valve and discharged directly from the 85 boiler to the smoke box to abate the draft at any time desired.

One of the principal features of the present invention is to provide an improved means for abating the draft through the 100 fire box by providing means operating at a pressure less than the discharge pressure of the main pop-valve for discharging the steam from the source of boiler pressure into the smoke-box in opposition to the incoming 105 draft from the firebox whereby to abate the draft not only by the reduction of the vacuum in the smoke-box due to the expansion of the steam as in my prior application, but also by the velocity of the steam thus ar- 110

ranged to discharge directly into the face of the incoming draft.

Another feature of this invention resides in providing the most effective projecting of the steam into the smoke-box in opposition to the incoming draft from the fire-box by locating the discharge nozzle so as to spread the steam jet substantially across as well as along the bottom of the smoke-box and directly to the rear thereof into the face of the incoming draft from the firebox.

Yet another feature of this invention resides in the novel construction of the steam discharge nozzle and its arrangement within the smoke-box for accomplishing the function above set forth.

A further object of this invention resides in providing a warning signal adapted to be operated by the steam discharging from the auxiliary pop-valve so that the engineer or fireman will instantly know when to reduce his rate of firing.

Still another object of this invention resides in providing means for permanently fastening the globe valve in the steam discharge connection between the auxiliary pop-valve and the smoke-box at the desired extent of opening so that when such valve is once set for any particular locomotive it may be finally fastened in such adjusted position, so as to prevent its being changed by the operatives.

These and other objects will in part be obvious and will in part be hereinafter more fully disclosed.

In the drawings, which show by way of illustration one embodiment of the invention:—

Figure 1 is a side elevation of a modern locomotive in dotted outline, with the invention applied thereto in unbroken lines;

Fig. 2 is a front view showing the relative position of the location of the steam discharge nozzle;

Fig. 3 is a side elevation of the nozzle projecting into the front of the smoke-box, and

Fig. 4 is an end view of the steam discharging nozzle.

Referring now to the drawings in detail, the invention shows in general the same generic construction set forth in my before-mentioned pending application and includes a small pipe 1, preferably one inch inside diameter, connected to the steam dome 2 (or to the steam distributor if preferred) and provided with a small auxiliary angle pop-valve 3. This valve is set to pop off at a pressure slightly less than that of the usual

or main pop-valve (not shown in the drawings) and, therefore, acts in advance of it. The discharge of steam from the auxiliary pop-valve 3 is conducted by any convenient route through a small pipe 4 to a globe valve 5, which globe valve is placed at any

convenient point between the pop-valve 3 and the front end of the smoke-box. From the globe valve 5 the pipe 4 extends to an angle 6, thence to a T 7 and thence, by any convenient route avoiding existing appliances, to a point 8 on the smoke-box where it passes tightly through the shell or wall 8 of the smoke-box. The present invention differs in specific details by the particular location of this steam discharge into the smoke-box and the construction of the discharge nozzle for accomplishing the improved functional features hereinbefore enumerated. If preferred, the pipe 4 may pass through the shell of the smoke-box at the bottom and near the front, and then connect with the nozzle 12, discharging horizontally and to the rear, instead of passing through the front wall of the smoke-box.

In the preferred embodiment of my improved construction the end of the pipe 4 at the point 8 where it projects into the smoke-box is placed preferably near the front, close to the bottom, directly under the axis of the smoke-box, and directed horizontally to the rear thereof. The discharge end of this pipe 4 is flattened, so as to form a nozzle 12 oblong in section. By means of this construction, the steam discharged into the smoke-box meets and opposes the draught from the fire and is spread by means of the oblong section of the orifice of the nozzle, over the bottom of the smoke-box. This is the most effective location and the most desirable shape and direction for the jet of steam. It is evident however, that other nozzle designs and other locations for the steam discharge are contemplated for accomplishing this function.

For the purpose of reducing the pressure of steam below that at which the auxiliary pop-valve 3 is set, or for temporarily reducing the draft when the fire is being "jerked", or when the locomotive is passing through tunnels, standing still, or is lightly loaded, or for any other reason a material reduction in the draft is needed, there is provided in addition to the automatic discharge of steam from the auxiliary pop-valve into the smoke-box, a pipe 9 preferably one inch inside diameter, fitted with a globe valve 10 placed within the cab in convenient reach of the fireman. This pipe extends from the T 11 near the dome 2 to connect the source of boiler pressure directly with the pipe 4.

For the purpose of discharging condensed steam collecting in the pipe 4, a very minute hole is formed in this pipe at the lowest point in its course. This hole may be connected with a drain pipe or other draining device if desired.

Actual trial has shown that there is no standard setting for all locomotives for the globe valve 5 which governs the amount

of steam passing through the pipe 4. Each individual locomotive requires a different adjustment of this valve for its most effective operation, and after the valve has once 5 been carefully adjusted it must be fixed to prevent alteration. Any desired means for fixing the valve in set position may be utilized or if desired the stem may be sawed off after the adjustment is made.

10 Actual trial has proven conclusively that the invention hereinbefore described materially reduces the amount of coal fed to the fire because the fireman naturally reduces the rate of his firing as soon as he 15 becomes aware that the auxiliary pop-valve is discharging. With the construction set forth in my prior application it was necessary, on all but certain kinds of mechanically fired locomotives, for the fireman to open the fire-door in order to judge from the appearance of the fire whether the pop-valve was operating. This was not only inconvenient but highly undesirable, since the cold draft of air passing in through the fire 20 door tends to cause leaks at the ends of the boiler flues as is well known to those skilled in the art. For the purpose of avoiding this objectionable practice, I have provided 25 an audible or visible automatic signal for

30 apprising the fireman when the auxiliary pop-valve is operating, or when steam is being discharged through pipe 4, or pipe 9, into the smoke-box. The preferred form of this means comprises a minute pipe 13, 35 much smaller than the pipe 4, connected to pipe 4, following any route and terminating outside of and preferably near the front or rear of the cab to a point in sight or hearing of the fireman. The end of this 40 pipe 13 is provided with a very minute whistle 15 which is blown by the escaping steam from pipe 13. This whistle provides a distinctive noise readily audible to the fireman from within the cab. Obviously in 45 lieu of the whistle, a visible signal of escaping vapor may be used. In this event a minute orifice may be made at a desired point in plain view of the fireman. It will be observed that both the visible and audible 50 signal will be operated either by steam discharging from the auxiliary pop-valve or by the by-pass pipe 9.

In the general operation of the regulator, the globe valve 10 is normally completely 55 closed and the globe valve 5 permanently fixed open to such an extent as may be required. When the boiler pressure reaches an intensity great enough to operate the small auxiliary pop-valve 3, but not quite 60 great enough to operate the usual large or main pop-valve (not shown), steam passes at high pressure through pipe 4 and globe valve 5, and continues through the T 7 and pipe 4 to point 8 on the smoke-box shell, 65 thence through this shell where it expands

within the smoke-box, and its pressure, owing to this free expansion becomes very greatly reduced but yet remains sufficient to counteract and lessen but not destroy, the vacuum. So also the velocity of this jet 70 discharging from the flattened nozzle 12, sweeps the steam along and spreads it across the bottom of the smoke-box as indicated by the arrow 15' in Figure 1 to oppose the draft from the fire-box indicated by the arrow 16, Figure 1, thereby assisting in abating the draft through the fire-box. With this moderation of the draft the rate of combustion is reduced, the boiler pressure falls, the small auxiliary pop-valve 3 closes, 75 further waste of steam is prevented, and the draft on the fire is automatically and immediately restored to its former intensity. The whole operation tends to anticipate and prevent the waste of steam through the 80 large pop-valve, with its accompanying noise, and the excessive use of fuel. The pipes 1, 4 and 9 and their fittings are purposely small so that at no time, through the oversight of the fireman or other unforeseen cause, can a sufficient amount of steam 85 pass through them to cause an objectionable back-draft through the fire door and grates.

It is obvious that this invention contemplates other means for discharging steam from the source of pressure into the smoke-box in advance of the discharge of the main pop-valve into the atmosphere. The claims are therefore, not to be regarded as limited 90 by the one embodiment disclosed, but also are intended to include the use of only one globe or other valve without the use of the auxiliary pop-valve.

Having thus described the invention, what 105 I claim as new and desire to secure by Letters-Patent, is—

1. In a locomotive combustion regulator, the combination with a source of boiler pressure, the usual pop-valve, means operating at 110 a pressure less than the discharge pressure of the main pop-valve for discharging steam from said source of boiler pressure into the smoke-box in opposition to the incoming draft from the firebox whereby to abate the 115 draft by the velocity of the steam discharge as well as by the reduction of the vacuum in the smoke-box due to the expansion of the steam.

2. In a locomotive combustion regulator, 120 the combination with a source of boiler pressure, the main pop valve, an auxiliary pop-valve connected to said source of pressure and adapted to discharge at a pressure slightly below the discharge pressure of the main pop-valve, and means for discharging the steam from said auxiliary valve into the smoke box in opposition to the incoming draft from the firebox whereby to abate the 125 draft from the fire by the velocity of the 130

steam discharge as well as by the reduction of the vacuum in the smoke-box due to the expansion of the steam.

3. In a locomotive combustion regulator, 5 the combination with a source of boiler pressure, the main pop-valve, an auxiliary pop-valve connected to said source of pressure and adapted to discharge at a pressure slightly below the discharge pressure of the 10 main pop-valve, and a nozzle connected to said auxiliary pop-valve and disposed at the front of the lower portion of the smoke-box in position to jet the steam therefrom rear- 15 wardly in the direction of the firebox in op- 20 position to the incoming draft therefrom, whereby to abate the draft from the fire by the velocity of steam discharge in addition to reducing the smoke-box vacuum by the 25 expansion of the steam from the nozzle.
4. In a locomotive combustion regulator, 30 the combination with a source of boiler pressure, the main pop valve, an auxiliary pop- 35 valve connected to said source of pressure and adapted to discharge at a pressure slightly below the discharge pressure of the main pop-valve, and a substantially flat, wide-mouthed nozzle connected to said auxiliary pop-valve and arranged within the smoke-box at the lower front portion there- 40 of whereby to discharge steam directly over the bottom of the smoke-box toward the firebox into the face of the incoming draft therefrom to abate the draft by means of the velocity of discharge of the steam as well as by the expansion of the steam.
5. In a locomotive combustion regulator, 45 the combination with a source of boiler pressure, the main pop valve, an auxiliary pop- 50 valve connected to said source of pressure and adapted to discharge at a pressure slightly below the discharge pressure of the main pop-valve, means connecting the dis- 55 charge of said auxiliary valve with the smoke-box to moderate the draft through the firebox, and a signal connected to said last- 60 named means operable by the steam dis- charge from said auxiliary valve.

6. In a locomotive combustion regulator, 45 the combination with a source of boiler pressure, the main pop valve, an auxiliary pop- 50 valve connected to said source of pressure and adapted to discharge at a pressure slightly below the discharge pressure of the main pop-valve, means connecting the dis- 55 charge of said auxiliary valve with the smoke-box to moderate the draft through the firebox, and a signal located near the cab and connected to said last-named means so as to be supplied by the steam dis- 60 charge from said auxiliary pop-valve.

7. In a locomotive combustion regulator, 65 the combination with a source of boiler pressure, a main pop-valve, an auxiliary pop- 70 valve connected to said source of pressure and adapted to automatically discharge steam from said source of boiler pressure into said smoke-box to moderate the draft, said means acting in advance of the discharge of the main pop-valve, a valved by-pass for dis- 75 charging steam directly from said source of boiler pressure into said smoke-box, a signal located near the cab and connected to the means for discharging steam into said smoke-box, said connection being disposed so that said signal is operated either by the 80 steam discharge from said pop-valve or said by-pass.

In testimony whereof, I affix my signature.

EDMUND T. D. MYERS, JR.
